UNITED STATES PATENT OFFICE.

JULIUS ROBBE, OF MEMPHIS, TENNESSEE.

TRAIN-SPEED CONTROL.

1,274,330.

Specification of Letters Patent. Patented July 30, 1918.

Application filed October 13, 1917. Serial No. 196,532.

To all whom it may concern:

Be it known that I, JULIUS ROBBE, a citizen of the United States, residing at Memphis, in the county of Shelby and State of Tennessee, have invented new and useful Improvements in Train-Speed Controls, of which the following is a specification.

This invention relates to apparatus for automatically controlling the speed of trains and the principal object of the invention is to provide means controlled by the speed of the train for first giving warning when the train is exceeding a predetermined speed and then applying the brakes if the speed is increased.

A further object of the invention is to provide means for indicating the speed the train is traveling and other means for registering the speed traveled per hour for the trip. Another object of the invention is to provide a device of this character which is simple and durable in construction, reliable and efficient in operation and one which can be manufactured and placed upon the market at a minimum cost.

The invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is an elevation of the invention with parts broken away and parts shown in section.

Fig. 2 is a section on line 2—2 of Fig. 1. Figs. 3, 4 and 5 are views of details.

In carrying out my invention I locate a casing 1, preferably in the cab of the engine and this casing contains the operating parts of my device. The device consists of a centrifugal governor 2 located in the casing and connected with one of the wheels 3 of the train by any suitable means, those shown consisting of a shaft 4 resiliently supported on a bracket 5 carried by any suitable part of the train. This shaft carries a pulley 6 which is connected with the car wheel 3 by means of a belt 7. The shaft 4 is provided with a small gear 8 which meshes with the gear 9 carried by a shaft 10 and which is suitably supported in the bracket 11. The

shaft 10 is connected to the governor by flexible shafting 12 which may be of the well known flexible type or which may be provided with universal joints at desired positions. The bracket 11 is slidably connected with the bracket 5 by means of the rods 13 and the coil springs 14. These springs while permitting the proper transmission of the power to the shaft 4 from the car wheel will prevent damage to the parts from jars and the like.

The governor 2 is supported in standards 15 and 16, and the standard 15 supports the upper end of the shafting 12. This part of the shafting carries a toothed wheel 17 which meshes with a like wheel 18 secured to the stub shaft 19 of the governor. The governor may be of any desired type though it is shown as consisting of the pivoted arms 20 connected with the weights 21. The other end of the governor is pivoted to a collar 22 carried by a rotating shaft 23 which is mounted in a sleeve 24, preferably of rectangular shape and mounted to have sliding movement in the standard 16. The shaft 23 is provided with roller bearings 25. A rod 26 is connected with the sleeve 24 and at its other end said rod is connected to a coiled spring 28 which is connected with the piston 29 secured to the end of the rod. In this way the governor is normally held in a retracted position.

A part of the train pipe indicated by the reference numeral 30 is extended up into the casing 1 and its end enters a cylinder 31, communication between the cylinder and pipe being normally closed by a valve 32 connected with a piston 33 by a rod 34. 35 represents a port in the wall of the cylinder. 36 represents an air-chest located on the cylinder 31 and in which operates a sliding valve 37. This valve is provided with a projecting part 38 which comes in the path of an adjustable finger 39 located on the rod 26. A branch pipe 40 leads from the main pipe into the valve chamber of the air-chest and this pipe is provided with an extension 41 the end of which is opposite a port 42 leading from the valve chamber to the air-chest and this part of the air-chest communicates with the cylinder by the port 43. Another part of the air-chest is connected with a whistle 44 by a pipe 45. The valve is provided with suitable openings so that on the movement of the same the branch 40 is first put in communication with that part of the

- air-chest which is connected with the whistle to sound the same and then on the further movement of the valve the extension 41 is put in communication with the other part 5 of the chest to allow the air to enter the cylinder 31 to operate the piston 33 to open the valve 32 and thus permit the pressure in the train pipe to escape through the port 35.
- 10 An indicating hand 46 is pivoted to a bracket 47 mounted on the air-chest and operates over a suitable dial 48 provided with indicating marks to show the engineer the rate of speed the train is traveling. At its 15 lower end this hand is connected with the rod 26 as shown.
- 49 indicates a disk mounted on the pivot 50 carried by the bracket 47 and this disk is adapted to support a suitable sheet provided 20 with suitable indicating marks to represent the miles traveled by the train. A recording device, shown as a pencil carried by the hand 46 co-operates with this sheet to form a record of the variations of the speed traveled 25 by the train during the course of the trip. As shown in Fig. 3 the pencil 51 is carried by a cylinder 52 connected with the hand 46 by an extension 53 and said pencil being forced into contact with the sheet on the dial 30 by means of the spring 54 in the cylinder.
- The disk is rotated by the following means: A shaft 55 mounted in the standards 15 and 16 is connected with the shafting 12 by means of the gears 56 and this 35 shaft drives a stub shaft 57 by means of a belt 58 passing over the gears 59 and 60. The stub shaft carries a pin-wheel 61, the pins of which engage with perforations 62 arranged in the edge of the disk 49.
- 40 It will thus be seen that as the governor is operated by the speed of the train it will cause the rod 26 to move toward the right, in Fig. 1, against the action of the spring 28 so that at a predetermined speed the ad- 45 justable finger 39 will come in contact with the projection 38 on the slide valve 37 so as to move said valve to put the branch 40 in communication with the whistle 44 and thus sound the alarm, thus giving the engineer 50 warning that he is going too fast. If he should neglect to reduce the speed the further movement of the rod 26 will cause the slide valve to move farther so as to put the
- branch 40 in communication with the cylinder. This action will cause the piston to 55 slide forwardly to open the valve 32 to permit the pressure in the train line to escape through the port 35 and thus apply the brakes. As the rod 26 moves forwardly it will cause the hand 46 to travel over the 60 dial 48 so that the engineer may see the speed he is traveling at that moment, it being understood that the casing is provided with a suitable window in front of said dial. As the hand travels over the dial the pencil 65 will also move over the sheet on the disk thus making a permanent record of the speed of the train throughout the trip.
- It is thought from the foregoing description that the advantages and novel features 70 of my invention will be readily apparent.
- I desire it to be understood that I may make slight changes in the construction and in the combination and arrangement of the several parts, provided that such changes 75 fall within the scope of the appended claims.
- What I claim is:—
1. A device of the class described comprising a centrifugal governor, means for connecting the same to one of the train wheels, 80 a rod connected with the governor, alarm mechanism operated by the rod at one step in the movement thereof, brake applying means operated by said rod in another step of its movement, a dial, an indicating hand 85 operating over the same, said hand being connected with the rod, and recording means associated with said hand.
2. A device of the class described comprising a centrifugal governor, means for connecting the same with one of the train wheels, a disk, means for rotating the same by the train wheel, a rod adapted to be moved longitudinally by the governor, an indicating hand connected with the rod and moved thereby, a dial co-operating with said hand, a pencil connected with the hand and engaging with the disk, an adjustable finger on the rod, a slide valve having a projection adapted to engage with said finger, alarm 95 and brake applying mechanisms actuated by said valve, and a spring connected with said rod for returning the parts to normal position.

In testimony whereof I affix my signature. 105
JULIUS ROBBE.
